UNITED STATES PATENT OFFICE.

MARY A. MAXWELL, OF BOSTON, MASSACHUSETTS.

EMBROIDERY-FRAME.

SPECIFICATION forming part of Letters Patent No. 244,816, dated July 26, 1881.

Application filed April 2, 1881. (No model.)

To all whom it may concern:

Be it known that I, MARY A. MAXWELL, of Boston, in the county of Suffolk and State of Massachusetts, have invented a new and useful Improvement in Embroidery-Frames, of which the following is a specification.

This invention relates to embroidery-frames; and it consists in the construction and combination of parts hereinafter set forth and claimed.

10 Referring to the drawings, Figure 1 is a perspective view of an embroidery-frame as connected with a bracket and embodying my invention. Fig. 2 is a side view of the bracket in connection with the socket. Fig. 3 shows the semi-circular support as folded within the circular holder. Fig. 4 represents a circular holder made of thin sheet metal, bent over at right angles on each side. Fig. 5 shows a portion of the holder or hook and of the semicircular support, with the method of connecting the two. Figs. 6 and 7 are sections of the hoop or holder and support and the socket.

15 A represents a circular holder, made of any suitable material, but preferably of thin metal, 25 of any desirable width at its perimeter and about sixteen inches in diameter, more or less, as may be required. The outer surface of the circular holder, A, may be provided with a covering of felt or other suitable material, to aid 30 in holding the cloth while being embroidered and prevent it from slipping. The cloth is secured to the holder A by means of a strap, s, of leather or other suitable material.

When the hoop and its support are made of 35 thin sheet metal the sides are to be turned inward at right angles, as shown at A' and B' in Figs. 4 and 5, and the ends of the semicircular support B' are inserted in a socket, m, on the inner side of the hoop A', as shown in Fig. 5. 40 By this means I obtain a support or hoop possessing all the necessary strength and durability, while it is much lighter and less expensive to manufacture than when made of plain hoop form.

45 To opposite inner sides of the circular holder, A, is pivoted a semicircular metal strap, B, of a less diameter than the holder A, so as to admit of its being turned up and folded within the said holder, as shown in Fig. 3. The ends of 50 the metal strip or support B may be provided with thumb-screws m, as shown, so as to hold

the two parts firmly together in any desired position.

To the under side of the lower portion of the support B is attached, either permanently, or 55 it may be by a thumb-screw, a ball, a, fitting within a socket, i, so as to constitute a ball-and-socket joint. The socket is formed in two parts, one part, c, constituting a part of the arm of the bracket, and the other part, d, consisting 60 of half the socket i, and a plate which is formed with a beveled edge, l, which fits within a recess in the arm c of the bracket and abuts against a shoulder, j, in the same, as shown in Figs. 1 and 2.

65 The bracket is constructed with the jaws f' and provided with a thumb-screw, g, by which the whole frame may be attached to the edge of a table, shelf, or other support, C, as shown.

The detachable semi-socket and plate d are 70 secured to the recessed arm c by means of a thumb-screw, e, as shown.

The holder A, instead of being circular, may be of any other desired shape, such as round, oval, or other shape.

75 What I claim as my invention, and desire to secure by Letters Patent, is—

1. In an embroidery-frame, the combination of the ring A and support B, with the ball a, clamping-socket i, and a clamp for attachment 80 to the table or other article, substantially as set forth.

2. In an embroidery-frame, the combination of ring A, support B, ball a, and the socket in two sections clamped together by screw e, one 85 of said sections being on recessed bracket-arm c and the other being on detachable bracket-arm d, having shoulder l, substantially as set forth.

3. An embroidery-frame consisting of the 90 hollow sheet-metal ring and support, a clamping-socket, and a clamp for attaching the frame to a table or other article, substantially as set forth.

In testimony whereof I have signed my name 95 to this specification in the presence of two subscribing witnesses.

MARY A. MAXWELL.

Witnesses:

Jos. H. ADAMS,
B. O'HARA.
